(57) **CLAIM**

The ornamental design for a bow string release, as shown and described.

DESCRIPTION

FIG. 1 is a perspective view of the first embodiment of a bow string release, showing my new design; FIG. 2 is a side view thereof; FIG. 3 is an opposite side view thereof; FIG. 4 is a front view thereof; FIG. 5 is a rear view thereof; FIG. 6 is a top view thereof; FIG. 7 is a bottom view thereof; FIG. 8 is a perspective view of the second embodiment of a bow string release; FIG. 9 is a side view thereof; FIG. 10 is an opposite side view thereof; FIG. 11 is a front view thereof; FIG. 12 is a rear view thereof; FIG. 13 is a top view thereof; FIG. 14 is a bottom view thereof; and, FIG. 15 is a cross-sectional view taken along line 15-15, illustrated in FIGS. 4 and 11. The broken line in the FIGS. 4 and 11 discloses the section cut lines and forms no part of the claimed design.

1 Claim, 15 Drawing Sheets
